UNITED STATES PATENT OFFICE.

PAUL M. HOTCHKIN, OF CHICAGO, ILLINOIS, ASSIGNOR TO NATIONAL X-RAY
REFLECTOR CO., OF CHICAGO, ILLINOIS, A CORPORATION OF ILLINOIS.

LIGHTING-FIXTURE.

1,318,757.

Specification of Letters Patent. Patented Oct. 14, 1919.

Application filed June 20, 1917. Serial No. 175,830.

To all whom it may concern:

Be it known that I, PAUL M. HOTCHKIN, a citizen of the United States, residing at Chicago, in the county of Cook and State 5 of Illinois, have invented a certain new and useful Improvement in Lighting-Fixtures, of which the following is a specification.

My invention relates to those lighting fixtures, which are termed indirect, but in 10 which the ornamental appearance of the fixture is increased by surrounding the reflector with a glass bowl and then reflecting some of the direct light rays on to said bowl, thereby imparting a desirable luminosity 15 to it, and removing the frequently heard objection that the source of light is unseen, and yet having it so screened as to avoid the extremely deleterious action of direct light upon the eyes.

20 My means of accomplishing the foregoing objects may be more readily understood by having reference to the accompanying drawings, which are hereunto annexed and are a part of this specification, in which:

25 The figure is a vertical sectional view of a fixture constructed in accordance with my improvement.

Similar reference numerals refer to similar parts throughout the entire description.

30 The drawing shows my improvement applied to a lighting fixture which is suspended from the ceiling. The fixture is provided with the usual canopy 6 from which depend a plurality of chains 5 which support at 35 their lower ends a fixture body 2, which, as shown in the drawing, is an ornamental ring. Inside of this ring is mounted an annular member 3 which is preferably formed of metal, although any other suitable material can be employed. The upper portion of this annular member 3 flares upwardly and outwardly, the lower portion being bent at an angle to the upper portion and is flared downwardly and outwardly. The lower

45 surface of this downwardly and outwardly flaring portion is preferably enameled white, forming a reflecting surface. A plurality of arms 7 formed of metal, are spot-welded to the annular member 3 and extend inwardly

and downwardly therefrom, forming a support for a reflector 8, which is designed to receive the light flux from an electric light bulb 9 and direct the light rays upwardly and outwardly, the major portion of the light rays passing to the ceiling whence they 55 are redirected to the useful plane.

A portion of the rays which are directed outwardly will, however, strike the reflecting portion of the annular member 3 and be redirected downwardly causing an illumination 60 of a glass bowl 4 which is suitably supported by the fixture body 2.

The result of this construction is at once apparent. The fixture has, due to the reflector 8, all the desirable results of a total 65 indirect fixture, while the white enameled metal surface of the ring will reflect a sufficient number of lumens to impart a pleasing amount of illumination to the bowl 4, thus serving to bring out its ornamentation, 70 and greatly adding to the beauty of the fixture. If desired the outer surface of the reflector 8 can be coated with aluminum, as may also the arms 7, which will tend to increase the illumination of the bowl 4. 75

Having described my invention what I regard as new, and desire to secure by Letters Patent is:

1. A lighting fixture comprising the combination with a source of light of a fixture 80 body, an annular member mounted inside the fixture body the upper portion of which flares upwardly and outwardly, the lower portion being bent at an angle thereto and flaring downwardly and outwardly, the 85 lower surface of the downwardly and outwardly flaring portion forming a reflecting surface which reflects the light rays downwardly, a reflector which directs the light flux upwardly and outwardly mounted inside of the glass bowl but in spaced relation thereto, and means carried by said annular member to support said reflector.

2. A lighting fixture comprising the combination with a source of light of a fixture 95 body, an annular member mounted inside the fixture body the upper portion of which flares upwardly and outwardly, the lower

portion being bent at an angle thereto and flaring downwardly and outwardly, the lower surface of the downwardly and outwardly flaring portion being enameled forming a reflecting surface which reflects the light rays downwardly, a reflector which directs the light flux upwardly and outwardly mounted inside of the glass bowl but in spaced relation thereto, means carried by said annular member to support said reflector, and means to support said fixture body.

In testimony whereof, I have signed the foregoing specification.

PAUL M. HOTCHKIN.
